CLAIM

I claim the ornamental design for a moldable earpiece, as shown and described.

DESCRIPTION

FIG. 1 is a top and right side perspective view of a moldable earpiece, embodying our new moldable earpiece design;

FIG. 2 is a front plan view thereof;

FIG. 3 is a rear plan view thereof;

FIG. 4 is a left side elevation view thereof;

FIG. 5 is a right side elevation view thereof;

FIG. 6 is a top elevation view thereof; and,

FIG. 7 is a bottom elevation view thereof.

In the drawing, the claimed design is defined by the shaded surfaces; the broken lines depict environment that form no part of the claimed design.
